UNITED STATES PATENT OFFICE

135,094

DESIGN FOR A TOY

Earl Glenn Stalnaker, Chicago, Ill.

Application May 14, 1942, Serial No. 106,897

Term of patent 3½ years

To all whom it may concern:

Be it known that I, Earl G. Stalnaker, a citizen of the United States, residing at Chicago, in the county of Cook and State of Illinois, have invented a new, original, and ornamental Design for a Toy, of which the following is a specification, reference being had to the accompanying drawing, forming a part thereof.

In the drawing,
showing my new design; and

Fig. 2 is an edge view thereof.

I claim:

The ornamental design for a toy, substantially as shown.

EARL GLENN STALNAKER.
